UNITED STATES PATENT OFFICE.

JERRY J. HOLECEK, OF NEW YORK, N. Y.

CRAVAT-STRETCHER.

1,185,401.

Specification of Letters Patent. Patented May 30, 1916.

Application filed May 4, 1915. Serial No. 25,756.

To all whom it may concern:

Be it known that I, JERRY J. HOLECEK, a citizen of the United States, residing at New York, in the county of New York and State of New York, have invented new and useful Improvements in Cravat-Stretchers, of which the following is a specification.

This invention relates to stretchers especially adapted to be used for holding neckties or cravats in a stretched condition and it consists in the novel features hereinafter described and claimed.

An object of the invention is to provide a stretcher adapted to be used in the capacity indicated and which is of simple and durable structure and which may be easily and quickly applied to the cravat, and which, when applied, efficiently holds the cravat in a stretched condition.

20 In the accompanying drawing: Figure 1 is a perspective view of a four-in-hand tie or cravat showing the stretching device applied thereto. Figs. 2 and 3 are side elevations of the stretching device, one being 25 larger than the other.

As illustrated in the accompanying drawing, the cravat 1 is in the form of the usual four-in-hand tie. These ties are open at their ends and after they have been used one 30 or more times they become wrinkled. The structure hereinafter described is adapted to be inserted in the ends of the tie when the same is removed from the neck of a wearer, and if the tie is slightly dampened 35 and permitted to remain at rest with the stretching devices inserted in the ends thereof, the material of which the tie is composed will be sufficiently stretched to remove therefrom all wrinkles and consequently, when 40 it is desired to wear the tie again it is in a flat smooth condition and a presentable bow may be readily tied in the same.

The stretchers which are used at the opposite ends of the tie are of the same general 45 structural arrangement, the only difference being that one stretcher is of larger size than the other stretcher. Each stretcher includes a transversely disposed bar 2 to the ends of which are pivotally attached rods 3. The 50 rods 3 are preferably formed from sheet metal and the free end portions of the said rods are twisted as at 4 whereby the inner

surfaces of the broader portions of the rods lie opposite each other. A pin 5 passes transversely through the twisted portion 4 of the rods 3 and is provided at its ends with heads 6 adapted to engage the outer surfaces of the twisted extremities 4 of the rods 3. A spring 7 surrounds the intermediate portion of the pin 5 and the said spring at its opposite end bears against the said surfaces of the twisted extremities 4 of the rods 3. The spring 7 is under tension with a tendency to hold the extremities 4 in contact with the heads 6 of the pin 5.

When the stretching devices are inserted in the ends of a tie the twisted extremities 4 of the rods 3 are pressed toward each other against the tension of the spring 7 and the stretcher is inserted in the end of the tie with the bar 2 inserted foremost. When the stretcher is in proper position within the end of the tie the twisted extremities 4 of the rods 3 are released and the tension of the spring 7 comes into play and the said rods 75 3 are forced into contact with the inner sides of the fold at the edges of the tie. After the stretcher has been inserted in the tie, or prior to the insertion of the stretcher, the tie may be dampened slightly and, consequently the spring 7 will hold the opposite side portions of the tie in a stretched condition and this will remove any wrinkles which might be in the material of the tie and when the tie has become dry it will be in a 85 flat condition suitable for wearing and may be readily manipulated for forming the same into an attractive bow or knot.

From the above description taken in conjunction with the accompanying drawing it 90 will be seen that a tie stretcher of simple and durable structure is provided and that the same may be easily and quickly applied to a tie and removed from the same, and when used upon a tie, will efficiently remove 95 wrinkles from the tie and leave the same in a desired flat and smooth condition.

Having described the invention, what is claimed as new is:

A tie stretcher comprising a cross bar, 100 rods pivotally connected with the ends of the cross bar and provided at their free end portions with extremities twisted at right angles to the portions which are pivotally

connected with the cross bar, a pin passing transversely through the said extremities and provided at its ends with heads adapted to engage the outer surfaces of the said extremities and limit the outward swinging movement of the rods, and a spring surrounding the intermediate portion of the pin and bearing at its ends against the inner

surfaces of the said twisted extremities of the rods. 10

In testimony whereof I affix my signature in presence of two witnesses.

JERRY J. HOLECEK.
